UNITED STATES PATENT OFFICE.

HENRY EDWIN HODGSON, OF CLECKHEATON, AND JAMES HARTLEY, OF MANCHESTER, ENGLAND.

MOLDING-MACHINE.

No. 857,173.

Specification of Letters Patent.

Patented June 18, 1907.

Application filed December 12, 1905. Serial No. 291,474.

To all whom it may concern.

Be it known that we, HENRY EDWIN HODGSON, a subject of the King of Great Britain and Ireland, and residing at Brookhouse Iron Works, Cleckheaton, in the county of York, England, and JAMES HARTLEY, a subject of the King of Great Britain and Ireland, and residing at Little Peter street, Manchester, in the county of Lancaster, England, have invented certain new and useful Improvements in and Relating to Molding-Machines for Use in Casting Metal, of which the following is a specification.

This invention relates to molding machines in which the box is reversed to enable it to be withdrawn from the pattern plate.

The invention is particularly applicable to such machines as are operated by pneumatic pressure.

20 The object is to provide a machine of greatly simplified construction, capable of rapid operation, and free from faults caused by the accumulation of sand in any of the working parts.

25 The invention consists in the particular machine to be hereinafter described and also in various detail improvements in the mechanism in that machine.

The following are the improved points of 30 construction in this machine—the general method of operation of which is well known.

(1) The improved method of suspending the pattern table on toggle links provided with buffer nuts and washers and the improved

35 arrangements by which sand is prevented from obtaining access to the working parts.

(2) The improved movable drawing table and oil controlling device for regulating accurately the gradual withdrawal of the mold

40 from the pattern. (3) The means provided for preventing the ramming cylinder from being operated when the pattern table is moved away from its position directly over the ramming cylinder. These features will be more

45 clearly understood from the accompanying drawings in which,

Figure 1 is a part sectional side elevation of a molding machine operated by compressed air in accordance with the invention,

50 the section being taken on the line A B of Fig. 2. Fig. 2 is an end view of the machine shown in Fig. 1; certain details have been omitted from these views for the sake of clearness. Fig. 3 is a vertical section on line

C—D of Fig. 4. Fig. 4 is an end elevation 55 partly in section, and Fig. 5 is a horizontal section on line E—F of Fig. 4. Fig. 6 is a detail view to an enlarged scale of part of the pattern table carriage showing the means by which the cock supplying air to the ramming 60 cylinder is locked when the carriage is moved away from the running position. Fig. 7 is another view of this device looking in the direction of the arrow X, in Fig. 6.

In carrying the invention into effect according to the particular form shown in the accompanying drawings where all the improvements are shown applied to the same machine, we provide a suitable strong bed plate, *a*, to which is attached a powerful 65 cross-head, *b*, carrying a projection, *c*, against which the molding box, *d*, is thrust in order to ram the sand. The molding box, *d*, is mounted upon a rotating table, *e*, which carries the pattern. The rotating table, *e*, is 70 carried by toggle links, *g*, which pass through oscillating sleeves, *f*, attached to a frame, *h*, which is carried by rollers, *j*, running on rails, *k*.

The toggle links, *g*, are working fits in the 80 holes formed in the oscillating sleeves, *f*, and the upper ends of the links are furnished with nuts, *m*, which are shown in Fig. 6. The buffers consist of washers, *n*, covered by caps, *o*, screwed on the end of the toggle links, 85 *g*. The nuts, *m*, support the weight of the table, pattern, molding box and sand, while the sliding toggles, *g*, permit of the table being forced violently upward when the blow from a pneumatic ram, *q*, situated below the 90 ramming head, *c*, is given. By delivering a blow in this manner the sand in the molding box, *d*, is rammed by means of the projecting head, *c*, and the required mold thereby produced. Extensions, *s*, are provided 95 on the frame, *h*, these extensions being sufficiently long to effectually cover the rails and rollers and thereby prevent any undue wear by the presence of sand on the working surfaces.

The toggle links, *g*, also form a convenient means of suspending the table, *e*, and molding box, *d*, in a manner to avoid any inconvenience in the movements or adjustments by admission of sand to the trunnion or 105 trunnion slides formerly employed in machines of this type.

Suitable catches, *r*, are provided to lock

the box against the rotating table. These catches are shown as arranged for holding the molding box open end upward, but they also hold the boxes open end downward.

5 Below the rails, *k*, and at the opposite ends of the carriage, *h*, to that at which the ramming cylinder *q*, is arranged, a pneumatic drawing cylinder, *t*, is provided, having a head, *u*, adapted to raise a carriage, *v*, from 10 rails, *w*, placed below the level of the pattern table rails, *k*. This cylinder is adapted to be raised by pneumatic pressure supplied through the pipe, *x*, but it is maintained in its raised position by hydraulic pressure, that is, the pressure of a liquid—the liquid preferably used, however, is oil.

15 A chamber, *y*, (Fig. 3) located immediately below the head, *u*, is filled with oil and a valve controlled central passage, *z*, leads to 20 the central cylinder, *2*, which acts as a hydraulic cylinder while the annulus, *3*, above the head, *4*, constitutes the pneumatic cylinder. A non-return valve, *5*, and a conical stop valve, *6*, operated by a spindle, *7*, passing 25 outward and provided with an operating handle, *31*, are employed for effecting the control of the oil-flow in and out of the central hydraulic cylinder as hereinafter set forth. The cylinder, *t*, has at its lower end 30 layers of fibrous cushioning material, *9*, and a cylinder hood, *8*, is also provided to cover the exterior of the cylinder, *t*, and the exposed working surface of the central head, *4*. Packing rings, *10*, are placed at the top end 35 of the central head, *4*, for the purpose of preventing egress of air from the annulus, *3*. A packing gland, *12*, is provided to prevent egress of oil from the central hydraulic cylinder, *2*.

40 The general operation of this machine is as follows:—The pattern is fixed to the pattern table, *e*, and the molding box or flask, *d*, is placed over the table embracing the pattern. Sand is then filled into the flask and the carriage, *h*, moved into the position, shown in 45 Fig. 1 directly over the ramming cylinder, *c*. A gas ring burner, *15*, (Fig. 2) may be provided below the pattern table for the purpose of heating the pattern and so facilitating the 50 withdrawal of the mold. Compressed air is then admitted to the ramming cylinder which thereby causes the head, *13*, provided with a fibrous cushion, *14*, (Fig. 2) to rise. The flask, *d*, filled with sand is thus carried 55 forcibly upward against the ramming head, *c*, and the sand rammed into the contour of the pattern. One or more blows may be given as found necessary. The pattern table with the flask thereon is then lowered on to the 60 carriage, *h*, being suspended therefrom by the toggles, *g*, and the carriage, *h*, is removed to the left in Fig. 1. The pattern table, *e*, is now revolved about its pivotal connection, *16*, with the toggle links, *g*, and the drawing 65 carriage, *v*, is raised by the cylinder, *t*. The

flask, *d*, is thus resting on the drawing carriage with that side down which was originally up when on the pattern table. When the drawing carriage, *v*, is raised by the pneumatic cylinder, *t*, oil flows from the chamber, *y*, in the head, *u*, through the non-return valve, *5*, into the central hydraulic cylinder, *2*, and is there imprisoned. The lowering of the drawing carriage, *v*, may be readily effected and controlled by opening the conical valve, *6*. The drawing may thus be effected as slowly and steadily as desired, whereby damage to the mold is prevented.

70 Any of the well known rapping devices are also provided on the pattern table or drawing table, such devices being operated either mechanically or by air as desired.

75 For the purpose of preventing the drawing table rotating or swiveling round while the mold is being withdrawn strong guides are provided which render the withdrawal perfectly straight. The construction of these guides will be readily seen from Figs. 4 and 5. Fixed to the head, *u*, of the drawing cylinder, *t*, there is a guide block, *32*, having a dust hood or cover, *17*, and a projection, *18*, which engages in a groove formed in a fixed pillar guide, *19*. The broad faces, *20*, thus constitute an efficient means for insuring the straight withdrawal of the mold. Means for preventing the accidental opening of the valve which controls the admission of air to the ramming cylinder, *q*, are also preferably provided. This device is shown in enlarged detail in Figs. 6 and 7. Air from the compressor is led into the box, *21*, by a pipe, *22*, and from this box a connection piece, *23*, provided with a flexible tubing leads air to the drawing cylinder, *t*, the admission of such air being controlled by a cock or valve, *24*. 80 A pipe, *25*, controlled by a cock, *26*, conducts compressed air from the box, *21*, to the admission pipe, *27*, (Fig. 1) of the ramming cylinder, *q*. The cock, *26*, has a handle, *28*, provided with a projection, *29*, adapted to engage with a shelf, *30*, carried by the cover extensions, *s*, whenever the carriage, *h*, is moved out of its position immediately above the ramming cylinder. As will be readily understood, the cock, *26*, when in the position shown in Fig. 6, is closed, and cannot be operated until the pattern table is moved into ramming position again.

85 The improvements constitute in the main a machine which is simple in construction and less liable to damage than molding machines of this type hitherto known.

90 Having thus described our invention what we claim as new and desire to secure by Letters Patent is:—

1. A sand molding machine having in combination, a revoluble pattern table adapted to carry a sand molding box; toggle link suspension gear for said revoluble pattern table; a ramming head and means for rais- 95 100 105 110 115 120 125 130

ing the table to ram the sand into the sand molding box; substantially as described.

2. A sand molding machine having in combination, a revoluble pattern table adapted to carry a sand molding box; toggle link suspension gear for said pattern table; a ramming head; and a power cylinder for raising the table to cause the ramming head to ram the sand into the sand molding box; substantially as described.

3. A sand molding machine having in combination a revoluble pattern table, toggle links supporting said revoluble table, pivoted guides for the toggle links, a molding box carried by the table, a power cylinder for raising said table, and a stationary ramming head against which the box is projected, substantially as described.

4. A sand molding machine having in combination a revoluble pattern table for carrying a molding box, a power ramming cylinder for raising the table; toggle links supporting said revoluble table; pivoted guides for the toggle links, buffers on said toggle links for avoiding shocks, and a stationary ramming head coacting with the table substantially as described.

5. A sand molding machine having in combination a revoluble pattern table for carrying a molding box, a horizontally movable carriage supporting said pattern table, toggle link suspension gear between said carriage and the revoluble pattern table, and a fixed ramming head coacting with the table, substantially as described.

6. A sand molding machine having in combination a revoluble pattern table for carrying a molding box, a horizontally movable carriage supporting said pattern table, toggle link suspension gear between said carriage and the revoluble pattern table, guides for the toggle links, said guides being pivotally mounted on the carriage, and a fixed ramming head coacting with the table, substantially as described.

7. A sand molding machine having in combination, a revoluble pattern table for carrying a molding box; a horizontally movable carriage supporting said pattern table; toggle link suspension gear between said carriage and table; guides for the toggle links said guide being pivotally mounted on the carriage, buffers on the toggle links for avoiding shock, a fixed ramming head, above the table and a power cylinder for raising the table to cause the ramming head to ram the sand into the mold substantially as described.

8. A sand molding machine having in combination a revoluble pattern table for carrying a molding box; trunnions on the table; links enveloping said trunnions and forming a pivoted support for the table; pivotally carried guides for said links; a bracket carrying said guides; a traversable carriage sup-

porting the bracket; rails for said carriage, a fixed ramming head above the table and means for raising the table to cause the head to ram the sand into the mold, substantially as described.

9. In combination with a sand molding machine having a pneumatically operated ramming cylinder and a horizontally movable pattern table, a horizontally movable pattern drawing table, a pneumatic drawing cylinder beneath the drawing table, an hydraulic cylinder concentrically arranged with respect to the pneumatic cylinder, a head or plate raised by the pneumatic drawing cylinder adapted to contact with the drawing table, and a piston on said head or plate adapted to work in the hydraulic cylinder, substantially as described.

10. In combination with a sand molding machine having a pneumatically operated ramming cylinder and a horizontally movable pattern table, a horizontally movable pattern drawing table, a pneumatic drawing cylinder beneath the drawing table, an hydraulic cylinder concentrically arranged with respect to the pneumatic cylinder, a head or plate raised by the pneumatic drawing cylinder and adapted to contact with the drawing table, a piston on said head or plate adapted to work in the hydraulic cylinder, and a hollow chamber containing the liquid which forms the working agent in the hydraulic cylinder, substantially as described.

11. In combination with a sand molding machine having a pneumatically operated ramming cylinder and a horizontally movable pattern table, a horizontally movable pattern drawing table, a pneumatic drawing cylinder beneath the table, an hydraulic cylinder concentrically arranged with respect to the pneumatic cylinder, a head or plate raised by the pneumatic drawing cylinder and adapted to contact with the drawing table, a piston on said head or plate adapted to work in the hydraulic cylinder, a hollow chamber having communication with the hydraulic cylinder for supplying the liquid which forms the working agent in said hydraulic cylinder, and a non-return valve in said communication arranged to automatically admit the liquid to the said hydraulic cylinder.

12. In combination with a sand molding machine having a pneumatically operated ramming cylinder and a horizontally movable pattern table, a horizontally movable pattern drawing table, a pneumatic drawing cylinder beneath said drawing table, an hydraulic cylinder concentrically arranged with respect to said pneumatic cylinder, a head or plate carried by the pneumatic drawing cylinder, a piston on said head or plate adapted to work in the hydraulic cylinder, a hollow chamber for containing the liquid which forms the working agent in the hy-

draulic cylinder having communication with said hydraulic cylinder, a non-return valve arranged in said communication to automatically admit the liquid to the said hydraulic cylinder, and a controlling valve for regulating the exit of liquid from the said hydraulic cylinder, substantially as described.

13. In combination with a sand molding machine means for withdrawing the pattern

c from the mold comprising a table, a guided head located below the table a hollow oil chamber within said head, a passage leading

15 from said hollow oil chamber, a centrally disposed cylinder to which said passage leads, non-return and regulating valves governing the flow of oil to and from said cylinder through the said passage, an annular pneumatic piston head (4) and a cylinder adapted to slide over said head substantially as de-

20 scribed.

14. In a power sand molding machine having a horizontally movable pattern carriage, and a fluid operated ramming cylinder means for preventing the accidental admission of working fluid to the ramming cylinder when the pattern table is not in proper position beneath the ramming head comprising a cock (26) having a handle (28) and a projection (29), a shelf (30) carried by the longitudinally movable carriage co-acting with the projection (29) on the handle, substantially as described.

In testimony whereof we have signed our names to this specification in the presence of two subscribing witnesses.
